CLAIM

The ornamental design for an earring and pin display, as shown and described.

DESCRIPTION

FIG. 1 is a front elevational view of an earring and pin display, showing my new design;

FIG. 2 is a top plan view thereof;

FIG. 3 is a rear elevational view thereof;

FIG. 4 is a bottom plan view thereof;

FIG. 5 is a right elevational view thereof; and,

FIG. 6 is a left elevational view thereof.

The broken line showing of the doll is for illustrative purposes only and forms no part of the claimed design.
